(57) **CLAIM**

The ornamental design for a massage belt, as shown and described.

DESCRIPTION

FIG. 1 is a front, right and bottom perspective view of a massage belt, showing my new design;

FIG. 2 is a rear, left and top perspective view thereof;

FIG. 3 is a front view thereof;

FIG. 4 is a rear view thereof;

FIG. 5 is a right side view thereof;

FIG. 6 is a left side view thereof;

FIG. 7 is an enlarged top plan view thereof;

FIG. 8 is an enlarged bottom plan view thereof;

FIG. 9 is an enlarged view of portion of FIG. 1 thereof; and,
FIG. 10 is an enlarged view of portion of FIG. 1 thereof.

The dot-dash broken lines depict the boundaries of the

enlargements that form no part of the claimed design.
